UNITED STATES PATENT OFFICE.

THOMAS DAILEY, OF JACKSON, MICHIGAN.

FENCE-POST.

SPECIFICATION forming part of Letters Patent No. 399,021, dated March 5, 1889.

Application filed December 4, 1888. Serial No. 292,656. (No model.)

To all whom it may concern:

Be it known that I, THOMAS DAILEY, a citizen of the United States, residing at Jackson, in the county of Jackson and State of Michigan, have invented a new and useful Improvement 5 in Fence-Posts, of which the following is a specification.

The invention relates to improvements in fence-posts; and it consists in a certain novel 10 construction and combination of devices, fully described hereinafter in connection with the accompanying drawings, and specifically pointed out in the claims.

In the drawings, Figure 1 is a perspective 15 view of a portion of a fence constructed with posts embodying my improvements. Fig. 2 is a detail view of one of the improved posts. Fig. 3 is a side view, partly in section, of the same, showing its lower end set in the ground.

20 Referring by letter to the drawings, A designates the improved post, in one side of which is formed a series of rectangular notches, B B, in which are fitted the ends of the fence rails or boards C C, which are secured in place 25 by the transverse bolts D D, extending through perforations d d in the post and registering perforations c c in the said rails or boards.

30 Downwardly and inwardly inclined transverse grooves E E are formed in the post at the lower inner angles of the notches B B, the said grooves communicating with the notches, and F F represent wires extending longitudinally along the fence and fitting in the grooves E. These wires are fitted in the grooves before 35 the rails or boards are arranged in the notches, and after the rails or boards are secured in place the wires cannot be detached, as the former close the outer or open sides of the grooves.

40 The lower end of the post is tapered, as shown at G, and a lateral shoulder, H, is formed at the upper end of the said tapered portion to bear on the surface of the ground.

The lower tapered end of the post is driven 45 into the ground until the shoulder bears thereon, and the shoulder forms a brace to prevent the upper end of the post from swaying laterally.

The advantage of the wire when used in combination with the rails or boards is that 50 it prevents stock from pushing the rails or boards off and also strengthens the fence longitudinally. The wires are preferably placed close to the lower edges of the rails, whereby when the stock attempt to push the rails off 55 they will also press against the wires and be thereby prevented from accomplishing their purpose.

The wires may be used independently of the rails, in which case it is preferred to bolt 60 blocks in the notches of the posts to hold the wires in their grooves.

Having thus described the invention, I claim—

1. The fence-post provided with transverse 65 notches B B, and grooves E E at the lower inner angles of the said notches, in combination with the wires fitting in the said grooves, and the rails or boards fitting in the notches and held in place by bolts passing through the 70 posts, substantially as specified.

2. A fence-post provided in one side with shallow rail-notches B B, and having grooves 75 g g inclining downwardly and inwardly from the inner lower angles of the said notches, substantially as specified.

In testimony that I claim the foregoing as my own I have hereto affixed my mark in presence of two witnesses.

his
THOMAS X DAILEY.
